(57) **CLAIM**

The ornamental design for a socket wrench, as shown.

DESCRIPTION

FIG. 1 is a perspective view of a socket wrench according to the invention illustrating the top and right side of the invention;

FIG. 2 is a top elevation view of the socket wrench of FIG. 1; FIG. 3 is a bottom elevation view of the socket wrench of FIG. 1;

FIG. 4 is a right side elevation view of the socket wrench of FIG. 1;

FIG. 5 is a left side elevation view of the socket wrench of FIG. 1;

FIG. 6 is a front side elevation view of the socket wrench of FIG. 1;

FIG. 7 is a back side elevation view of the socket wrench of FIG. 1

FIG. 8 is a perspective view of a second embodiment of the socket wrench of FIG. 1, the difference being the disclaiming as indicated in the drawing by the location of the broken lines and the removal of the flex-head;

FIG. 9 is a top elevation view of the socket wrench of FIG. 8; FIG. 10 is a bottom elevation view of the socket wrench of FIG. 8;

FIG. 11 is a right side elevation view of the socket wrench of FIG. 8;

FIG. 12 is a left side elevation view of the socket wrench of FIG. 8;

FIG. 13 is a front side elevation view of the socket wrench of FIG. 8; and,

FIG. 14 is a back side elevation view of the socket wrench of FIG. 8.

Petitioner disclaims the shape and configuration of the features of those portions shown in broken lines.
